UNITED STATES PATENT OFFICE.

ARTHUR HEAGELE, OF BROOKLYN, NEW YORK.

WATER-BACK FOR GAS-STOVES.

1,101,279.

Specification of Letters Patent. Patented June 23, 1914.

Application filed February 14, 1914. Serial No. 818,763.

To all whom it may concern:

Be it known that I, ARTHUR HEAGELE, a citizen of the United States, residing at Brooklyn, in the county of Kings and State 5 of New York, have invented certain new and useful Improvements in Water-Backs for Gas-Stoves, of which the following is a full, clear, and exact specification.

This invention relates to waterbacks or 10 water heaters especially designed to be used on gas stoves for the purpose of heating water at the same time that the gas burner is being used for cooking purposes.

The principal object of the invention is to 15 provide a waterback for gas stoves which will heat water in a minimum space of time and without detracting materially from the heat supplied to a cooking vessel placed over the burner in the usual way.

20 Other objects will appear as the description proceeds.

The invention will be first hereinafter described in connection with the accompanying drawings, which constitute a part of this 25 specification, and then more specifically defined in the claims at the end of the description.

In the accompanying drawings, wherein 30 similar reference characters are used throughout the several views to designate corresponding parts:—Figure 1 is a vertical sectional view of a waterback constructed in accordance with my invention and applied to a gas burner, the latter being modified slightly in construction to adapt it to 35 my purpose. Fig. 2 is a plan view of the assembled device shown in Fig. 1. Fig. 3 is a detailed plan view of the burner and Fig. 4 is an enlarged detail sectional view 40 to illustrate how the flames from the burner play upon the bottom and the inner surfaces of the tubular passages in the waterback.

Referring more particularly to the drawings, A designates the waterback which may be generally flat and circular in form and which is connected to a suitable receptacle 45 for holding the hot water, as the tank B, by the circulating pipes b, b'. The waterback may be further formed with a central air circulating passage a' and with a plurality of scattered gas passages a, it being understood that the waterback as a whole is 50 hollow, so that the water contained therein comes in intimate contact with the walls of

said gas passages as well as the top and bottom thereof.

The gas burner C may be of the usual or any well known type having a plurality of gas emitting openings c in its upper surface. 60 The gas passages a in the waterback are arranged in vertical alinement with certain of these gas emitting openings in the burner, preferably with alternate ones of said openings, as best illustrated in Figs. 1 and 3. 65 The result is that the flames from some of the openings c in the burner will play upon the bottom of the waterback, while the flames from others of said openings will play into the passages a in the waterback. 70

In order to obtain the best results from these latter openings which are arranged in vertical alinement with the passages a in the waterback, extension tubes c' are fitted in

said openings, which tubes project well into 75

the passages a, as clearly shown in Figs. 1 and 4. By this means, the flames from said

tubes are carried through the passages a in the waterback and come in direct contact with the bottom D of a cooking vessel, Fig. 80

4, without materially detracting from the heating power of the burner provided for

cooking purposes. At the same time, these

flames impinge upon the inner surfaces of

the passages a and serve to superheat the

water in the waterback. It will further be

noted that the heat from these flames after

striking the bottom of the cooking vessel

will be thrown back upon the top of the

waterback, thereby constituting an addi-

90 tional means of superheating the water in

the waterback. It will thus be seen, and in

this connection attention is directed espe-

cially to Fig. 4, that the waterback is sim-

ultaneously heated at the bottom by the flames

95 from the openings c which are not equipped

with extension tubes, laterally by the flames

playing in the passages a, and at the top by

the heat thrown downward by the bottom of

the cooking vessel. Accordingly, the water

100 in said waterback must be heated in a mini-

105 mum space of time. At the same time the

heat of said waterback itself will practically

make up for any loss of heat for cooking

purposes which would otherwise result by

110 reason of the fact that alternate jets of

flame which play upon the bottom of the

waterback do not come in contact with the

bottom of the cooking vessel.

The burner may be provided with a cen-

tral air circulating passage c^s in vertical alinement with the passage a' in the waterback, see Figs. 1, 2 and 3. The form of burner shown has radiating arms c^2 in which 5 some of the gas emitting openings are formed. It will be understood, however, that any other suitable form or style of burner may be used, if desired, and provided with the extension tubes c' in order to adapt 10 it for the purposes of my present invention.

Having thus described my invention, what I claim as new and desire to secure by Letters Patent of the United States is:—

1. The combination, with a gas burner 15 having gas emitting openings in its upper surface, of a waterback arranged over the burner and having passages therethrough distributed over its horizontal extent, and tubular extensions fitted around some of the 20 gas emitting openings in the burner and projecting into said passages in the waterback, said passages constituting continuations of said tubular extensions to carry the flames from said extensions to the upper 25 surface of the waterback, others of said gas emitting openings in the burner furnishing flames impinging on the lower surface of the waterback.

2. The combination, with a gas burner 30 having gas emitting openings in its upper surface, of a waterback arranged over the burner and having passages therethrough distributed over its horizontal extent in vertical alinement with alternate openings in 35 the burner, and tubular extensions fitted around said alined openings and projecting into said passages in the waterback, said passages constituting continuations of said tubular extensions to carry the flames from 40 said extensions to the upper surface of the waterback, the alternate non-alined openings in the burner furnishing flames impinging on the lower surface of the waterback.

3. The combination with a waterback 45 having passages therethrough, of a gas burner having alternate ones of its gas emitting openings provided with tubular projections extending into said passages in the waterback.

50 4. The combination with a waterback having passages therethrough, of a gas burner

having its gas emitting openings arranged in radial rows, alternate ones of said openings in each row being provided with tubular projections extending into the passages 55 in the waterback.

5. The combination, with a gas burner having gas emitting openings in its upper surface, of a flat waterback to lie over said burner and below a vessel to be heated, said waterback having passages therethrough in alinement with some of the gas emitting openings of the burner, and tubular extensions from said alined openings projecting into said passages, the latter constituting 65 continuations of said tubular extensions to carry the flames from said extensions to the upper surface of the waterback, others of said gas emitting openings in the burner furnishing flames to impinge on the lower 70 surface of the waterback.

6. The combination with a waterback having an air circulating passage disposed centrally thereof and a plurality of gas circulating passages radially arranged with respect to the air circulating passage, of a gas burner having a central air circulating opening in alinement with the air circulating passage in the waterback, and gas emitting 75 openings alternate ones of which are disposed in alinement with the gas circulating passages in the waterback.

7. The combination with a waterback having an air circulating passage disposed centrally thereof and a plurality of gas circulating passages radially arranged with respect to the air circulating passage, of a gas burner having a central air circulating opening in alinement with the air circulating passage in the waterback, and gas emitting 80 openings, alternate ones of which are disposed in alinement with the gas circulating passages in the waterback, and tubular projections from said alined openings extending 85 into said gas circulating passages. 90 95

In testimony whereof I have signed my name to this specification in the presence of two attesting witnesses.

ARTHUR HEAGELE.
